UNITED STATES PATENT OFFICE.

THOMAS F. BYRNE, OF PHOENIXVILLE, PENNSYLVANIA.

PLAITING APPARATUS.

SPECIFICATION forming part of Letters Patent No. 651,181, dated June 5, 1900.

Application filed December 11, 1899. Serial No. 739,950. (No model.)

To all whom it may concern:

Be it known that I, THOMAS F. BYRNE, a citizen of the United States, and a resident of Phoenixville, Chester county, Pennsylvania, 5 have invented certain Improvements in Machines for Inserting Tape into Lace Edgings, of which the following is a specification.

The object of my invention is to impart a certain amount of slack or fullness to a piece 10 of tape threaded into a strip or band of lace-work, such as that employed as edging for undergarments and the like, whereby a given length of such edging will contain a length of tape in excess of the length of the edging, 15 thereby providing projecting ends for forming a knot or bow.

In the accompanying drawings, Figure 1 is a view of a strip of lace edging with tape as inserted therein previous to my invention. 20 Fig. 2 is a view of a similar strip of edging with tape inserted therein by mechanism constituting my invention. Fig. 3 is a top or plan view of mechanism embodying my invention. Fig. 4 is a side view of one of the 25 elements of said mechanism. Fig. 5 is a sectional view of the other element of the same, and Fig. 6 is a front view of the same.

Lace edging of the character to which my invention relates consists of opposite side 30 portions *a a*, connected by transverse bars or rows of stitches *b*, and a tape *d* is threaded into such edging by passing it alternately under and over these transverse bars.

In machines which have heretofore been 35 devised for introducing the tape into the edging no provision was made for introducing the tape in excess—that is to say, a greater length of tape than the length of edging containing the same; but such excess of tape is necessary 40 in order that when a length of edging has been cut off to serve as a trimming for the neck or armhole of a garment the tape can be drawn out beyond the ends of the edging, so as to be tied in a knot or bow. In carrying 45 out my invention I take the edging, with the tape inserted therein, and feed it between rollers in such manner that the tape will be drawn forward faster than the edging, thus providing an excess of tape proportionate 50 to the difference in the rate of feed. This may be done by passing the edging between

rollers having the portion which acts upon the tape of greater diameter or traveling at a greater surface speed than the portion which acts upon the edging, although I prefer to use in connection with feed mechanism actuating upon the tape a device for frictionally retarding the side portions of the edging, while the central portion with the inserted tape is free from such frictional retardation. 60

In the drawings, 1 represents a roll having a shaft 2, which is mounted in a fixed bearing 3, and 4 represents a roll disposed directly above the roll 1 and having a shaft 5, which is mounted in a bearing 6, having rods 7 passing down through the lower bearing 3 and provided with heads 8, between which and shoulders on said lower bearing are interposed springs 9, a lever 10, mounted at one side of the lower bearing 3, acting upon a pin or stud 70 11 on the upper bearing 6, so that the latter can be raised and lowered as desired. The roll 4 has a raised central ring or band 12, which normally runs in contact with the lower roll 1, but can be removed from contact therewith by lifting the upper bearing 6. The shaft 5 of the upper roll 4 has a pulley 13 for receiving a suitable driving-belt, and said shaft also has a spur-pinion 14, which meshes with a spur-wheel 15 of somewhat larger diameter on the shaft of the lower roll, so that the central ring or band 12 of the upper roll 4 travels at a somewhat-higher surface speed than the lower roll 1. 75

In front of the structure which I have just described and at any suitable distance therefrom is another pair of rolls 16 and 17, the lower roll 16 being carried by a shaft which is adapted to fixed bearings in standards 18, while the shaft of the upper roll is adapted to 90 boxes which are acted upon by springs, the tension of which can be adjusted by means of screws 19, so as to cause the upper roll 17 to bear upon the lower roll 16 with any desired degree of pressure. The rolls 16 and 17 95 are centrally grooved for the reception of a tube 20, which extends some distance from the rolls 16 and 17 in the direction of the rolls 1 and 4. This tube has the lace edging strung upon it—that is to say, it is threaded through 100 the edging so that the central cross-bars of the latter are disposed alternately above and be-

low the tube, while the tape which is to be applied to the edging passes through the tube. The tape is therefore not subjected to the pressure of the rolls 16 and 17; but the edging 5 is confined between said rolls, and its movement is retarded to an extent dependent upon the pressure of said rolls against each other. Upper and lower guide-bars 21 and 22, disposed in front of the rolls 16 and 17, serve to 10 flatten out the side portions of said edging as it approaches the rolls, so that said side portions of the edging are properly fed between the portions of the rolls which flank the central grooves and are thereby subjected to the 15 desired retarding influence, the central portions of the guide-bars having flaring cone portions 23 and 24, and said bars also having beveled portions 25 and 26, so as to aid in the proper presentation of the edging to the rolls. 20 As the tape is continually subjected to the forward pull of the central ring or band 12 of the roll 4 and is free from any retarding influence other than that exerted upon it by the pressure of the cross-bars *b* of the edging, said 25 tape is fed forward faster than the edging, which, in addition to being retarded by the action of the rolls 16 and 17, is not continually acted upon by said band 12 of the roll 4, the latter acting only upon the cross-bars of the 30 edging and the side portions of said edging passing between the roll 1 and the portions of the roll 4, which flank the central band 12 and are less in diameter than the latter. As a consequence the desired excess of length of tape 35 is produced, as shown in Fig. 2, so that when a piece of edging of the desired length has been severed from the strip the tape can be pulled out so as to project from each end of

said piece of edging in order to form portions for being tied into bows or knots.

40

Having thus described my invention, I claim and desire to secure by Letters Patent—

1. In a machine of the character described, the combination of rolls for feeding forward a strip of lace edging having a tape inserted 45 therein, and provision for frictionally retarding the movement of the edging without like retardation of movement of the tape, substantially as specified.

2. In a machine of the character described, 50 the combination of a pair of rolls adapted to feed a strip of edging, one of said rolls having a raised ring or band for acting upon a tape inserted in said edging, and means for driving said roll at a higher rate of surface 55 speed than the roll with which it co-operates, substantially as specified.

3. In a machine of the character described, the combination of a pair of draft-rolls, with 60 a pair of frictional retarding-rollers grooved for the reception of a guide-tube for the edging and for the tape to be inserted therein, substantially as specified.

4. In a machine of the character described, 65 the combination of the frictional retarding-rolls, the guide-tube adapted to grooves in said rolls, and guide-bars in front of said rolls, substantially as specified.

In testimony whereof I have signed my name to this specification in the presence of 70 two subscribing witnesses.

THOS. F. BYRNE.
